UNITED STATES PATENT OFFICE.

DON W. NORTON, OF KALAMAZOO, MICHIGAN, ASSIGNOR TO AMERICAN SIGNS CORPORATION, OF KALAMAZOO, MICHIGAN.

DESIGN FOR A SIGN.

Application filed August 17, 1928. Serial No. 27,866. Term of patent 3½ years.

To all whom it may concern:

Be it known that I, DON W. NORTON, a citizen of the United States, residing at Kalamazoo, in the county of Kalamazoo and State of Michigan, have invented a new, original, and ornamental Design for Signs, of which the following is a specification, reference being had to the accompanying drawing forming a part thereof, in which:

Fig. 1 is a front view, and

Fig. 2 an edge view of a sign embodying my design, the cross hatching being calculated to indicate color.

I claim:

The ornamental design for a sign, as shown.

DON W. NORTON.
